UNITED STATES PATENT OFFICE

2,009,988

SUBSTITUTED GLYCEROLS AND PROCESS
OF PRODUCING SAME

George A. Emerson, San Francisco, Calif., assignor to Eli Lilly and Company, Indianapolis, Ind., a corporation of Indiana

No Drawing. Application June 13, 1934, Serial
No. 730,461

10 Claims. (Cl. 260—99.20)

It is the object of my invention to produce from certain fatty acids which are bactericidal or bacteriostatic to *M. lepræ*, water-soluble derivatives which have certain advantages over the original acids and their salts; particularly in that they have good water-solubility, are effective in the treatment of leprosy on either oral or parenteral administration, and are less irritating and better tolerated when their solutions are administered parenterally than are those acids themselves or any previously known derivatives thereof.

These new water-soluble derivatives, and certain intermediates which are included within the scope of my claims, are all compounds which are represented by the following general formula:

in which *x* equals 2 or 3, *Z* in at least one instance is the following fatty-acid radical:

and in at least one other instance is the following radical:

and *R* represents either hydrogen or a cyclic group of the class consisting of the cyclo-pentyl group, the cyclo-hexyl group, the cyclo-pentenyl group, and the cyclo-hexenyl group, *R'* represents either hydrogen or a straight-chain aliphatic group, only one of *R* and *R'* in any *Z* is hydrogen, the total number of carbon atoms in any *Z* which has carbon atoms is between 12 and 18 inclusive, *w* is an integer of the necessary value to make that number (12 to 18) of carbon atoms in that *Z*, and *T* is either hydrogen or an alkali metal or an alkaline-earth metal or ammonium or a substituted ammonium.

There are a number of fatty acids, and their salts, which are known to have bactericidal and bacteriostatic effect against *M. lepræ*, both in vitro and in vivo. The effects in vivo have in many cases been proven on leprous rats. The tests of my products in vivo have also been made on leprous rats.

These fatty acids which are known to have this bactericidal and bacteriostatic action against *M.*

lepræ may be represented by the following formula:

in which *R*, *R'*, and *w* have the same significance as stated above. Among these acids may be mentioned the following:

- a.* chaulmoogric acid;
- b.* hydnocarpic acid;
- c.* the total fatty acids of chaulmoogra oil, hydnocarpus oil, carpotroche oil, macrocarpa oil, and/or oil of gorli;
- d.* certain fatty acids containing between 12 and 18 carbon atoms, of the type disclosed in the Adams Patent No. 1,878,732, of August 23, 1932. But in general these fatty acids are not sufficiently soluble for effective use in the treatment of leprosy, and have other disadvantages; and when their salts have sufficient solubility, such salts also generally have certain irritating qualities which interfere with their effective administration. Some of these salts have other untoward physiological effects in addition to causing local irritation, such as the production of hemolysis, sclerosis, hematuria, nephritis, and liver damage. These untoward physiological effects are in many instances so great that they preclude continued parenteral use of the substances, even in cases where promising initial results had been obtained.

I have discovered that by introducing the effective radicals of these fatty acids in compounds of the type shown in Formula 1, and/or in readily obtained derivatives of such compounds, I am able to get both the desired solubility and the desired freedom from irritating, hemolytic, and sclerosing properties.

In general I form my new compounds by either of the following procedures:

Procedure A.—First I form a glycerol or ethylene-glycol ester of the initial fatty acid, by reacting the desired dichloro-hydrin or chloro-hydrin, or other halogen hydrin, with the sodium, potassium, ammonium, calcium, or other soluble salt of the desired fatty acid; or by reacting the free fatty acid with the desired glycol or glycerol, with heat. This yields a di- or mono-glyceride or an ethylene mono-glycolide, in which there is at least one unsubstituted hydroxyl, and sometimes (in the case of the mono-glycerides) two unsubstituted hydroxyls. The glyceride or ethylene glycolide thus obtained is caused to react with

15

20

25

30

35

40

45

50

55

phosphoric anhydride, to introduce a phosphoric-acid radical at one or each of the hydroxyl groups of the glyceride or ethylene glycolide. The meta-phosphoric ester of the glyceride or ethylene glycolide is first formed; and this may be converted into the phosphoric-acid ester by reaction with aqueous alcohol, and into a phosphate thereof by reaction with a suitable base, such as sodium carbonate or bicarbonate or hydroxide.

10 *Procedure B.*—First a suitable glycero-phosphoric acid or glyco-phosphoric acid, or conveniently its sodium salt, is suitably prepared; and in the presence of an excess of concentrated phosphoric acid as a condensing agent the desired fatty acid is added to it, and the mixture heated on a water bath until reaction occurs. Best results are obtained if the fatty acid is present slightly in excess of the theoretical amount needed. On completion of the reaction, the acid formed may be neutralized, as with sodium hydroxide, to form the salt; and the salt may be purified by recrystallization.

15 By these procedures, it is possible in the case of the glycerides to get a number of variations. The fatty-acid radical may be introduced at one or two of the three hydroxyl groups of the glycerol, and so may be phosphoric-acid radical; which makes possible the following glycerides:

30 *I. Mono-fatty-acid, mono-phosphoric-acid esters*

There are three varieties of these:

a. With the fatty-acid radical introduced at the middle hydroxyl of the glycerol, as indicated by the following formula:

40 in which AcP indicates the phosphoric-acid radical of Formula 3, and AcF the fatty-acid radical of Formula 2.

45 b. With the phosphoric-acid radical introduced at the middle hydroxyl of the glycerol, as shown by the following formula:

55 c. With the middle hydroxyl unsubstituted, as shown by the following formula:

II. Mono-fatty-acid, di-phosphoric-acid esters

65 There are two varieties of these:

a. With the fatty-acid radical introduced at the middle hydroxyl of the glycerol, as shown by the following formula:

75 b. With the fatty-acid radical introduced at

an end hydroxyl of the glycerol, as shown by the following formula:

III. Di-fatty-acid, mono-phosphoric-acid esters

There are two varieties of these:

a. With the phosphoric-acid radical introduced at the middle hydroxyl of the glycerol, as shown by the following formula:

b. With the phosphoric-acid radical introduced at an end hydroxyl of the glycerol, as shown by the following formula:

IV. In the case of the ethylene glycolides, the fatty-acid radical is introduced at one hydroxyl group and the phosphoric-acid radical at the other hydroxyl group of the original ethylene glycol, as indicated by the following formula:

In the case of some of these compounds, certain of the intermediate glycerides or ethylene glycolides are also new.

Further, in all of these instances where a phosphoric-acid radical has been introduced, it is possible to obtain salts. These salts may be alkali-metal salts, ammonium salts, or substituted-ammonium salts; obtainable by reacting these phosphoric-acid esters with a suitable alkali-metal carbonate or hydroxide, or with ammonium hydroxide, or with an alkyl amine such as NH_2-CH_2 or $\text{NH}(\text{CH}_3)_2$ or $\text{NH}_2-\text{CH}_2-\text{CH}_2-\text{OH}$.

45 The following are some examples of the various esters which are included in my invention; and of some of the new intermediates and salts.

Class I.—Mono-fatty-acid, mono-phosphoric-acid esters

b. Mono-chaulmoogryl- β -glycero-phosphoric acid is one example under this class. It is prepared, according to *Procedure B*, by heating one mole of β -glycero-phosphoric acid with somewhat less than one mole of chaulmoogric acid for 55 one hour at 100° C.

The acid was obtained as a soft, light brown, amorphous paste after clarification with bone charcoal. No definite melting point was obtained.

60 The sodium salt of this ester is obtained by neutralization of a concentrated alcoholic solution of the acid with a slight excess of NaHCO_3 , and evaporating to dryness in *vacuo*. This sodium salt is a water-soluble solid.

65 This ester and its salts are represented by the following formula:

in which T has the same significance as before. The salts may have a basic element or radical at one or both T's.

The other mono-chaulmoogryl-glycero-monophosphates may be similarly prepared.

Class II.—Mono-fatty-acid, di-phosphoric-acid esters

An example in this class is: 1,3-diphosphoryl-2-hydnocharyl-glycerol, prepared by heating β -monohydnocharpin (prepared from 2-halogen hydrin and Na hydnocharpate) with a large excess of P_2O_5 and isolating the acid as in reaction B.

The sodium salt of this ester is a water-soluble solid.

This ester and its salts are represented by the following formula:

in which T has the same significance as before.

Class III.—Di-fatty-acid, mono-phosphoric-acid esters

I give below several examples in sub-class a of this class:

a—1.—1,3-di-chaulmoogryl-glycero-phosphoric acid is prepared as follows:

Sodium chaulmoograte, which is known, is prepared by adding one mole of alcoholic sodium hydroxide to one mole of chaulmoogric acid, or to one mole of an alkyl chaulmoograte such as ethyl chaulmoograte, and evaporating to dryness. Other salts, as of potassium, ammonium, or calcium, may be similarly prepared.

1,3-di-chaulmoogrin, which is new with me, is prepared from 1,3-halogen hydrin, such as the 1,3-di-chlorohydrin above described, and a suitable salt of chaulmoogric acid. For example: one mole of 1,3-di-chloro-hydrin is mixed with slightly more than two moles of sodium chaulmoograte in a bomb tube or pressure bottle containing an atmosphere of nitrogen, and heated for several hours, say about 4 to 6 hours if at 120° and about 24 hours if at about 100° C.; and the reaction mixture is taken up in ether, desirably clarified by boiling with bone charcoal, then filtered and the filtrate reduced to a small volume by evaporation and then cooled to about 0° C. for 8 to 10 hours to precipitate excess sodium chaulmoograte, decanted or filtered, and any remaining ether removed by evaporation in vacuo. If desired, carbon dioxide or nitrogen may be bubbled through to aid the removal of the ether. The 1,3-di-chaulmoogrin thus obtained is a clear amber liquid, yielding small foci of white crystals on prolonged cooling at 0° C. It has an iodine number of 82.4. On prolonged heating at 60° in the air it decomposes, with some charring. It is an easily injectable liquid, suitable for intradermal or subcutaneous injection. It is represented by the following formula:

The foregoing method of producing 1,3-di-chaulmoogrin follows in general the Guth method for the preparation of diolein. (Zeitschrift für Biologie, vol. 44, p. 78, for 1903.)

1,3-di-chaulmoogryl-glycero-phosphoric acid is prepared from 1,3-di-chaulmoogrin and phosphorus pentoxide. Equal weights of these are mixed thoroughly, and the mixture heated for about thirty minutes at 100° C., during which time the mixture changes from a paste to a solid. (As within ten minutes the mixture becomes dark brown without external heating, the "several hours heating" at 100–110° C. as recommended in Hundeshagen's method for making distearyl-glycero-phosphoric acid seems unnecessary if not undesirable.) The solid thus obtained is put in 80% alcohol, and crushed; and the resultant material is filtered. The solid residue is then allowed to stand for 30 minutes under 80% alcohol at 30° C., to change any crude di-chaulmoogryl-glycero-metaphosphate present to di-chaulmoogryl-glycero-phosphate. The mass is then again filtered, and the solid residue remaining is extracted in a small volume of hot 95% alcohol, decanted, and the liquid evaporated to dryness in vacuo. The residue from the evaporation is a brown pasty substance, slightly soluble in water, having an iodine number of 73.1.

This free acid has not as yet been used therapeutically, for the therapeutic work involving it has been done with its salts. 1,3-di-chaul-

<p

moogryl-glycero-phosphoric acid and its salts are represented by the following formula:

The mono-sodium salt is a highly active bactericide.

5

in which T has the same significance as before. The salts may have a basic element or radical at one or both T's.

The sodium salt of 1,3-di-chaulmoogryl-glycero-phosphoric acid may be prepared by the addition of a slight excess of finely powdered sodium carbonate to a hot alcoholic solution of 1,3-di-chaulmoogryl-glycero-phosphoric acid, filtration, and subsequent removal of the solvent by vacuum evaporation. The salt may be recrystallized from benzene. When so recrystallized it is a light brown solid, soluble in water (requiring less than 10 parts of water to dissolve it), and has an iodine number of 70.7. The yield of this sodium salt usually exceeds 35% of theory, on the basis of the sodium chaulmoograte originally used.

This procedure follows in general that of Hundeshagen, (J. f. prakt. Chem., volume 136, p. 219, for the year 1883,) for distearyl-glycero-phosphoric acid.

The mono-sodium salt of 1,3-di-chaulmoogryl-glycero-phosphoric acid has been found to be beneficial in the treatment of leprosy in leprous rats, by intradermal, subcutaneous, intravenous, and intraperitoneal administration. An advantageous pH for the solution is around 8.0. By using the theoretical molecular proportions and evaporating to dryness, a fairly pure mono-sodium salt may be obtained.

The di-sodium salt of 1,3-di-chaulmoogryl-glycero-phosphoric acid is usually present to some extent with the mono-sodium salt at pH8. It may be obtained fairly pure by using the necessary molecular proportions in preparing the salt.

a-2.—1,3-di-di-n-heptyl-acetyl-glycero-phosphoric acid has been prepared by Procedure B given above, from di-n-heptyl acetic acid and sodium glycero-phosphate in the presence of an excess of concentrated phosphoric acid. It forms water-soluble salts with the alkali metals, ammonia, and alkyl amines. It is a brown, amorphous, waxy solid. Its sodium salt is a water-soluble, light-brown, amorphous solid. Its calcium salt, prepared from the acid and calcium carbonate, is a whitish, amorphous solid, slightly water-soluble.

60 The formula for 1,3-di-di-n-heptyl-acetyl-glycero-phosphoric acid and its salts is as follows:

in which T has the same significance as before. The salts, as of sodium or of calcium, may have a basic element or radical at either or both T's.

a-3.—1,3-di-cyclo-hexyl-ethyl-heptyl-acetyl-glycero-phosphoric acid may also be prepared, desirably by Procedure A; from cyclo-hexyl-ethyl-heptyl acetic acid and sodium glycero-phosphate, in the presence of an excess of concentrated phosphoric acid. The 1,3-di-cyclo-hexyl-ethyl-heptyl-acetyl-glycero-phosphoric acid is a solid, and forms water-soluble salts with the alkali-metals, ammonia, and alkyl amines.

The sodium salt is similar to the di-n-heptyl homologue, with about the same solubility. The ethanolamine salt forms a semi-solid paste, which in my experiments did not form a solid on prolonged vacuum desiccation.

This acid and its salts are represented by the following formula:

in which T has the same significance as before. The salts may have a basic element or radical at either or both T's.

Acids *a*-2 and *a*-3, like acid *a*-1, may be prepared by either Procedure A or Procedure B.

b.—2,3-di-chaulmoogryl-glycero-phosphoric acid may be prepared by either Procedure A or Procedure B.

In Procedure A, of course, a 2,3-halogen-hydrin is used instead of a 1,3-halogen-hydrin. The halogen-hydrin in either case may as conveniently be a di-bromo-hydrin as a di-chloro-hydrin.

2,3-di-bromo-hydrin is prepared from substantially anhydrous allyl alcohol and bromine, in known manner.

2,3-di-chaulmoogrin is prepared from 2,3-di-bromo-hydrin (or other 2,3-halogen-hydrin) and any salt of chaulmoogric acid, such as sodium chaulmoograte, in the same manner as has been described for the preparation of 1,3-di-chaulmoogrin from 1,3-chloro-hydrin and sodium chaulmoograte. The yields which have been obtained are rather poor.

2,3-di-chaulmoogryl-glycero-phosphoric acid may be prepared from 2,3-di-chaulmoogrin and phosphorous pentoxide, in the same manner as has already been described for the preparation of 1,3-di-chaulmoogryl-glycero-phosphoric acid. Its alkali-metal salts, such as the potassium salt for instance, may be obtained by precipitating a hot alcoholic solution of the acid with the carbonate of the desired alkali metal, such as potassium carbonate. These salts are freely water-soluble.

Ammonium salt and substituted-ammonium salts may also be prepared, in similar fashion.

2,3-di-chaulmoogryl-glycero-phosphoric acid

and its salts are represented by the following formula:

3. A substituted glycerol having the following formula:

in which AcP represents the phosphoric-acid radical, and AcP represents the following fatty-acid radical:

15 and R represents either hydrogen or a cyclic group of the class consisting of the cyclo-pentyl group, the cyclo-hexyl group, the cyclo-pentenyl group, and the cyclo-hexenyl group, R' represents either hydrogen or a straight-chain aliphatic group, only one of R and R' is hydrogen, the total number of carbon atoms in the fatty-acid radical is between 12 and 18 inclusive, w is an integer of the necessary value to make that number (12 to 18) of carbon atoms in the fatty-acid radical, and each phosphoric-acid radical has none, one, or both of its hydrogen atoms replaced by either an alkali metal, an alkaline-earth metal, ammonium, or a substituted ammonium.

4. A substituted glycerol having the following formula:

35 in which AcP represents the phosphoric-acid radical, and AcP represents the following fatty-acid radical:

45 and R represents either hydrogen or a cyclic group of the class consisting of the cyclo-pentyl group, the cyclo-hexyl group, the cyclo-pentenyl group, and the cyclo-hexenyl group, R' represents either hydrogen or a straight-chain aliphatic group, only one of R and R' in any fatty-acid radical is hydrogen, the total number of carbon atoms in any fatty-acid radical is between 12 and 18 inclusive, w is an integer of the necessary value to make that number (12 to 18) of carbon atoms in that fatty-acid radical, and the phosphoric-acid radical has none, one, or both of its hydrogen atoms replaced by either an alkali metal, an alkaline-earth metal, ammonium, or a substituted ammonium.

5. A substituted glycerol having the following formula:

65 in which AcP represents the phosphoric-acid radical, and AcP represents the following fatty-acid radical:

75 and R represents either hydrogen or a cyclic group of the class consisting of the cyclo-pentyl group, the cyclo-hexyl group, the cyclo-pentenyl group, and the cyclo-hexenyl group, R' represents either hydrogen or a straight-chain aliphatic

group, only one of R and R' in any fatty-acid radical is hydrogen, the total number of carbon atoms in any fatty-acid radical is between 12 and 18 inclusive, w is an integer of the necessary value to make that number (12 to 18) of carbon atoms in that fatty-acid radical, and the phosphoric-acid radical has none, one, or both of its hydrogen atoms replaced by either an alkali metal, an alkaline-earth metal, ammonium, or a substituted ammonium.

10 6. The process of producing a bactericidal compound, which consists in introducing a phosphoric-acid radical at at least one hydroxy group but at less than all of the hydroxy groups of glycerol or of ethylene glycol; and at least one other hydroxy group thereof introducing the following fatty-acid radical:

20 in which R represents either hydrogen or a cyclic group of the class consisting of the cyclo-pentyl group, the cyclo-hexyl group, the cyclo-pentenyl group, and the cyclo-hexenyl group, R' represents either hydrogen or a straight-chain aliphatic group, only one of R and R' in any fatty-acid radical is hydrogen, the total number of carbon atoms in any fatty-acid radical is between 12 and 18 inclusive, and w is an integer of the necessary value to make that number (12 to 18) of carbon atoms in that fatty-acid radical.

25 7. The process of producing a bactericidal compound, which consists in reacting a 2-carbon or 3-carbon halogen hydrin with a soluble salt of a fatty acid having the following fatty-acid radical:

35 in which R represents either hydrogen or a cyclic group of the class consisting of the cyclo-pentyl group, the cyclo-hexyl group, the cyclo-pentenyl group, and the cyclo-hexenyl group, R' represents either hydrogen or a straight-chain aliphatic group, only one of R and R' is hydrogen, the total number of carbon atoms is between 12 and 18 inclusive, and w is an integer of the necessary value to make that number (12 to 18) of carbon atoms in that fatty-acid radical; and then causing the glyceride or ethylene glycol so obtained to react with phosphoric anhydride; and treating the ester so obtained with a reagent which converts the ester into a soluble salt.

40 8. The process of producing a bactericidal compound, which consists in reacting a phosphoric-acid-radical-containing compound of the class consisting of glycero-phosphoric acid, glyco-phosphoric acid, and their soluble salts, in the presence of an excess of concentrated phosphoric acid as a condensing agent, with a fatty acid containing the following radical:

50 in which R represents either hydrogen or a cyclic group of the class consisting of the cyclo-pentyl group, the cyclo-hexyl group, the cyclo-pentenyl group, and the cyclo-hexenyl group, R' represents either hydrogen or a straight-chain aliphatic group, only one of R and R' is hydrogen, the total number of carbon atoms is between 12 and 18 inclusive, and w is an integer of the necessary value to make that number (12 to 18) of carbon atoms in that fatty-acid radical.

60 in which R represents either hydrogen or a cyclic group of the class consisting of the cyclo-pentyl group, the cyclo-hexyl group, the cyclo-pentenyl group, and the cyclo-hexenyl group, R' represents either hydrogen or a straight-chain aliphatic group, only one of R and R' is hydrogen, the total number of carbon atoms is between 12 and 18 inclusive, and w is an integer of the necessary value to make that number (12 to 18) of carbon atoms in that fatty-acid radical.

70 in which R represents either hydrogen or a cyclic group of the class consisting of the cyclo-pentyl group, the cyclo-hexyl group, the cyclo-pentenyl group, and the cyclo-hexenyl group, R' represents either hydrogen or a straight-chain aliphatic group, only one of R and R' is hydrogen, the total number of carbon atoms is between 12 and 18 inclusive, and w is an integer of the necessary value to make that number (12 to 18) of carbon atoms in that fatty-acid radical.

sary value to make that number (12 to 18) of carbon atoms in that fatty-acid radical. ing radical is introduced at each of two hydroxyl groups:

9. A substituted glycerol, in which the following radical is introduced at one hydroxyl group:

10 and in which the following radical is introduced at each of the other two hydroxyl groups:

15 and R represents either hydrogen or a cyclic group of the class consisting of the cyclo-pentyl group, the cyclo-hexyl group, the cyclo-hexenyl group, the cyclo-pentenyl group, and the cyclo-hexenyl group, R' represents either hydrogen or a straight-chain aliphatic group, only one of the R and R' in any radical containing both is hydrogen, the total number of carbon atoms in the first radical given above is between 12 and 18, w is an integer of the necessary value to make 15
 20 that number (12 to 18) of carbon atoms in that radical, and T is either hydrogen or an alkali metal or an alkaline-earth metal or ammonium or a substituted ammonium.

25 10. A substituted glycerol, in which the follow-

and in which the following radical is introduced at the third hydroxyl group:

and R represents either hydrogen or a cyclic group of the class consisting of the cyclo-pentyl group, the cyclo-hexyl group, the cyclo-pentenyl group, and the cyclo-hexenyl group, R' represents either hydrogen or a straight-chain aliphatic group, only one of the R and R' in any radical containing both is hydrogen, the total number of carbon atoms in the first radical given above is between 12 and 18, w is an integer of the necessary value to make 15
 20 that number (12 to 18) of carbon atoms in that radical, and T is either hydrogen or an alkali metal or an alkaline-earth metal or ammonium or 25 a substituted ammonium.

GEORGE A. EMERSON.
